(57) **CLAIM**

The ornamental design for a bottle for a drinkable product, therefor as shown and described.

DESCRIPTION

FIG. 1 is a top-front-left isometric view of a bottle for a drinkable product according to a first embodiment, with a removable cap (shown in phantom) engaged with the bottle for a drinkable product.

FIG. 2 is a left side elevation view of the bottle for a drinkable product of FIG. 1, the right side elevation view being identical thereof.

FIG. 3 is a front elevation view of the bottle for a drinkable product of FIG. 1, the rear elevation view being identical thereof.

FIG. 4 is a top plan view of the bottle for a drinkable product of FIG. 1.

FIG. 5 is a bottom plan view of the bottle for a drinkable product of FIG. 1.

FIG. 6 is a top-front-left isometric view of a bottle for a drinkable product according to a second embodiment.

FIG. 7 is a left side elevation view of the bottle for a drinkable product of FIG. 6, the right side elevation view being identical thereof.

FIG. 8 is a front elevation view of the bottle for a drinkable product of FIG. 6, the rear elevation view being identical thereof.

FIG. 9 is a top plan view of the bottle for a drinkable product of FIG. 6.

FIG. 10 is a bottom plan view of the bottle for a drinkable product of FIG. 6.

FIG. 11 is a top-front-left isometric view of a bottle for a drinkable product according to a third embodiment.

FIG. 12 is a left side elevation view of the bottle for a drinkable product of FIG. 11, the right side elevation view being identical thereof.

FIG. 13 is a front elevation view of the bottle for a drinkable product of FIG. 11, the rear elevation view being identical thereof.

FIG. 14 is a top plan view of the bottle for a drinkable product of FIG. 11; and,

FIG. 15 is a bottom plan view of the bottle for a drinkable product of FIG. 11.

The phantom lines showing the break in the bottle sidewall in FIGS. 11, 12 & 13 represent unclaimed boundaries. Any portion of the bottle for drinkable product between these boundaries forms no part of the claimed design. The remainder of the phantom lines shown throughout the drawing views illustrate the portions of the bottle for drinkable product that form no part of the claim thereof.
